UNITED STATES PATENT OFFICE

JACOB TELLER, OF CHICAGO, ILLINOIS, AND ARTHUR P. SCHULZ, OF BUFFALO, NEW YORK, ASSIGNORS TO TELLER CORPORATION, OF CHATTANOOGA, TENNESSEE, A CORPORATION OF TENNESSEE

DESIGN FOR A SIDE-OVEN CLOSED-TOP CABINET GAS OR ELECTRIC RANGE

Application filed October 21, 1930. Serial No. 37,331. Term of patent 7 years.

To all whom it may concern:

Be it known that we, JACOB TELLER and ARTHUR P. SCHULZ, citizens of the United States, residing, respectively, at Chicago and Berwyn, in the county of Cook and State of Illinois, have invented a new, original, and ornamental Design for a Side-Oven Closed-Top Cabinet Gas or Electric Range, of which the following is a specification, reference being had to the accompanying drawing, forming a part thereof.

Figure 1 is a front perspective view of the range with the top closed and,

Figure 2 is a similar view with the top raised and showing the ornamental appearance of the manifold shield.

We claim:

The ornamental design for a side oven closed top cabinet gas or electric range, as shown.

JACOB TELLER.
ARTHUR P. SCHULZ.
